FOLDING BOX WITH INTEGRAL SPOUT

Paul Johnson, Vancouver, British Columbia,
CanadaApplication June 9, 1934, Serial No. 729,858
In Canada April 21, 1934

1 Claim. (Cl. 229—17)

My invention relates to improvements in folding boxes with integral spouts, and has for an object to provide a box blank from cardboard, craftboard, pasteboard, or the like, with openings therein, cuts therethrough, scores thereon and shapes thereof, which is suitable for being folded into a tightly-closable receptacle, and which is provided with a spout formed from the spout blank and foldable into spout shape while being extended to its pouring position to a stop thereon and also being withdrawable to its flat shape wherewith the receptacle is closed.

Other objects of my improvement will appear as the description proceeds.

I attain these and other objects of my improvement with the mechanism illustrated in the accompanying sheet of drawing, which forms a part of this specification, in which Figure 1 is a plan view of a box blank from which a box with a foldable spout may be formed, Fig. 2 is a top plan view of the formed and pasted box, Fig. 3 is a repetition of Fig. 2 with the detachable piece removed, Fig. 4 is the same as Figs. 2 and 3 with the central portions of the outermost two layers of the material of the top folds broken away, Fig. 5 is a side elevation of the box with the spout extended and stopped in pouring position, Fig. 6 is a front elevation of Fig. 5, Fig. 7 is a plan view of the flattened spout piece, from which the remainder of the box blank is broken away, showing optional closure stops thereon, and Fig. 8 is a plan view of the end fragmentary portion of the second top fold showing an optional shape of the closing flap.

Similar characters refer to similar parts throughout the several views. Certain parts are broken away to show other parts hidden thereby.

With more particular reference to designated parts:

In the drawing of the box blank shown in Fig. 1 the solid lines indicate either margins or cuts made entirely through the material, while the dotted lines indicate scores or indentations to determine and localize the places for bending the material when forming the receptacles therefrom.

The box blank is substantially rectangular in exterior outline and consists of the front side 7, the rear end 8, the rear side 9, the front end 10, the first bottom fold 11, the second bottom fold 12, the third bottom fold 13, the fourth bottom fold 14, the side flap 15, the first top fold 17, the second top fold 18, the third top fold 19, the fourth top fold 16, the spout flap 34, 35 and 36 and the closing flap 47. While in Figs. 7 and 8 the

optional closed-position stops are at 43 and 45, and the optional closing-flap shape is shown at 41, 47.

An opening 41 is cut through the fourth top fold 16, an opening 45 is cut through the third top fold 18, and a deep notch 46 is cut into the end of the second top fold 19.

The corners of the box are formed on parallel dotted lines 20, 21, 22 and 23. The top folds are bent on the dotted line 24 and the bottom folds 10 are bent on the dotted line 25.

In addition to the opening 41 in the top fold 16 is the through cut 42. The ends of the opening 41 and the ends of the cut 42 are joined by the lines of through perforations 43 and 44. 15

The spout flap is partly severed from the top fold 17 by the spaced-apart, aligned through cuts 32 and 33 and the intervening space is marked by the dotted line b36 which is the locus of a hinge score. Centrally in the outer edge of the spout 20 flap is arcuate notch a36 the ends of which are connected to the ends of the hinge score b36 by the scores on the dotted lines 38 and 39. The side walls 40 and a40 of the spout have the arcuate edges 34 and 35, respectively, and the 25 stop lugs 37, 37 are attached thereto adjacent the cuts 32 and 33.

From the through bottom cuts 26, 27 and 28 and the through top cuts 29, 30 and 31 narrow pieces of the material have been removed to provide freedom for the folded parts when forming the box.

The box is shaped and glued in the usual manner with the number one top fold 17 on the inside of the top cover, the number two top fold 35 19 on the top thereof, the number three top fold 18 on the top of fold 19, and the number four top fold 16 on top of the number three fold and on the outside of the top of the box. The four top folds are glued together except that the 40 center of the detachable piece 49, which lays directly over the opening 45 on flap 18, the spout form and the flap 47 are not fastened by glue to the other parts. The side flap 15 is glued to end piece 10 and the bottom flaps 11, 12, 13 and 45 14 are glued together, forming the bottom of the box.

With the box thus completed and filled, say with salt, the top thereof appears as in Fig. 2. When it is desired to remove the first portion or 50 all of the salt from the box, the removable piece 49 is torn away by catching fast to an edge thereof in the opening 41 and tearing off the piece in the perforated lines 43 and 44. Then the top of the box appears as shown in Fig. 3.

To extend and shape the spout, insert the tine of a table fork, say, beneath the top flap 47 and, while lifting the flap with the tine, insert the same beneath the spout end at the notch a36 5 and, by lifting upward on the fork tine, extend the spout and form the same by drawing it through the opening 46 in the second top fold 19. The extended and shaped spout will appear as in Fig. 5 and Fig. 6 with the lugs 37, 37 bearing on 10 the bottom surface of the second top fold 19, whereby the further extension of the spout is prevented and the spout is fully open standing in the deep notch 46 of the second top fold. To withdraw the spout and close the openings in the 15 box top the spout is pushed downward into the top of the box through the openings 45 and 46 when the resilience of the material at the bends will cause the spout flap to again assume a nearly flat shape, closing the said openings. Fig. 4 is 20 used to show the appearance of the box top after the spout is withdrawn thereinto. Here, the central portion of the two outer folds are broken away and the closing flap 47 is shown to be, not overlying the spout end as in Fig. 3, but rather 25 beneath the spout where it serves to prevent the flattened spout from entering further beneath the box top, and also as a closure from within the cover to prevent the loss of salt through the box top in case the box be inverted. Furthermore, the particular location of the closing flap 30 47, as shown in Fig. 4, provides a finger-nail hold with which the subsequent extending of the spout is facilitated.

In the optional shape of spout blank, shown 35 in Fig. 7, the closure stop a34 is formed by a small boss extending laterally from the outer part of the spout side 34 and the transverse through

cut b34; and the closure stop a35 is formed from a small boss extending from the upper part of the spout side 35 laterally and the transverse through cut b35. When the spout is formed by being drawn outward through the opening 46, the said lateral bosses flex inwardly and pass through the opening and then assume again substantially the positions relative to the spout back 36 which they occupied when within the box. Thus, when the spout is withdrawn the lugs a34 10 and a35 protrude over the sides of the opening 46 and engage with the box top to prevent the spout from fully entering within the box. In the optional shape of the closing flap 47 shown in Fig. 8, the notch a47 is not deep enough to leave uncovered an opening in the closed box but it provides for more easily inserting the said opening 15 line.

I claim,—

A device of the kind described including, a 20 card-board box, three top folds glued together providing the top of the said box, a detachable piece in the topmost of the said three top folds, the two top folds beneath the said detachable 25 piece having openings therein registering therewith, a relatively shorter bottom top fold, a spout blank integral with the said short box-top fold disposable beneath the said registering openings adapted for extension through the said 30 openings to form a spout thereof and for withdrawal into the said box top to nearly close the said openings, and a closing flap fastened to one of the said three top folds disposed to close the small opening at the end of the withdrawn spout 35 to fully close the said box-top openings.

PAUL JOHNSON.
